APPARATUS FOR THE PROCESSING AND GROWTH OF CRYSTALLINE MATERIAL UNDER PRESSURE

Charles Harry Holliday, John Brian Mullin, and Barrie Wingfield Straughan, Malvern, England, assignors to National Research Development Corporation, London, England

Filed Oct. 25, 1968, Ser. No. 14,173

Claims priority, application Great Britain Apr. 26, 1968

Term of patent 14 years

Int. Cl. D24—99; D31

U.S. Cl. D16—2

FIG. 1 is a perspective view of the apparatus.

FIG. 2 is a top plan of the apparatus.

FIG. 3 is a front elevation of the apparatus.

FIG. 4 is an underneath plan of the apparatus.

The characteristic feature of our design resides in the central annular enlargement therein.

We claim:

The ornamental design for apparatus for the processing and growth of crystalline material under pressure, as shown and described.
